(Cl. D91—3)

Fig. 1 is an end elevational view of a flush valve, em-
bodying our new design;

Fig. 2 is a side elevational view thereof;

Fig. 3 is an end elevational view thereof taken from
the right of Fig. 2;

Fig. 4 is a top plan view thereof; and

Fig. 5 is a bottom plan view thereof.

The dominant features of our design reside in the por-
tions shown in full lines.

We claim:

The ornamental design for a flush valve, substantially
as shown and described.
